UNITED STATES PATENT OFFICE.

WILLIAM J. COOK AND MARTIN W. BREUER, OF DENVER, COLORADO, ASSIGNEES TO THE COOK RAILWAY SIGNAL COMPANY, OF DENVER, COLORADO, A CORPORATION OF COLORADO.

ELECTRICAL BLOCK-SIGNALING MECHANISM.

1,111,296.

Specification of Letters Patent. Patented Sept. 22, 1914.

Application filed January 17, 1912. Serial No. 671,687.

To all whom it may concern:

Be it known that we, WILLIAM J. COOK, and MARTIN W. BREUER, citizens of the United States, residing in the city and county of Denver, State of Colorado, have invented new and useful Improvements in Electrical Block-Signaling Mechanism; and we do declare the following to be a full, clear, and exact description of our invention, such as will enable others skilled in the art to which it appertains to make and use the same, reference being had to the accompanying drawings, and to the figures of reference marked thereon, which form a part of this specification.

Our invention relates to improvements in electrical block signaling mechanism and has for its object the provision of a simple, inexpensive and efficient mechanism for displaying signals whenever a train enters or leaves a block signaling section.

Another object of our invention resides in the provision of a signaling mechanism for preventing collisions and accidents.

Another object of our invention resides in the provision of a signaling mechanism for indicating when a train is in any block section and thus warn the crew of another train to remain without the block section until the said section has been cleared, or until the train within the said block section has moved out of the latter.

Another object of our invention resides in the provision of signal mechanism for insuring the positive display of danger and safety signals at the proper intervals and places.

With these and other objects in view, we will proceed to describe our invention with reference to the accompanying drawings.

In these drawings:—Figure 1 is a view, on a small scale, in elevation, of our improved signaling apparatus. Fig. 2 is a view of the upper part of the signaling apparatus, illustrating the semaphore arm in the two positions of danger and safety, the two signaling lamps being also illustrated. Fig. 3 is a detailed view, in elevation of the mechanism shown in Fig. 2, looking in the direction of the arrow 2, shown in Fig. 2. Fig. 4 is a side elevation of the operating parts of our improved signaling mechanism, taken on line 5—5. Fig. 5, in this view, the electrical circuit and a section

of the track is also illustrated. Fig. 5 is 55 a view looking in the direction of the arrow 5, Fig. 4. Fig. 6 is a detail side elevation similar to Fig. 4, with certain parts of the mechanism removed and indicating the position of the mechanism while displaying 60 the danger signals. Fig. 7 is a side elevation with certain parts removed and indicating the position of the mechanism while the same is in its movement to display the 65 danger signals.

The same reference characters indicate the same parts in all the views.

Let the numeral 8 designate a post or standard carrying the signal operating parts of our improved mechanism. This post or 70 standard is preferably formed in sections 9, 10, 12 and 13, certain parts of the operating mechanism being incased in the section 10, while the section 13 carries the semaphore arm and signal lights. These two 75 sections 10 and 13 are connected by means of the section 12 which is hollow and through which the connection between the signal operating mechanism and the signal proper is passed. From the foregoing description it will be seen that the different 80 sections of the post or standard may be readily disconnected for purposes of transportation.

Referring now to important features of 85 the invention, let the numeral 14 designate a section or block of the railway track. This section is insulated as shown at 15, from the adjacent section or blocks. The rails 16 and 17, of the section or block 14, 90 are respectively connected with the poles 18 and 19, of a source of electrical energy 20, by means of electrical conductors, 21 and 22. Near the opposite extremity of the block or section 14, of the track, is arranged 95 a relay 23. One terminal of the coil 27 of this relay is connected with the rail 17 of the block by an electrical conductor 28, while the other terminal of the coil is connected with the rail 16 by an electrical conductor 29. The core 30 of the relay 23, is provided at one extremity with a bar 31, the said bar forming a switch which is normally held in engagement with the contacts 32 and 33, which are connected by the 105 bar 31 when the relay 23 is energized. The source of electrical energy 20 supplies current to the relay 23, through the track

rails 16 and 17 and the connections here-tofore recited.

When the relay 23 is energized, the core 30 is drawn upwardly and carries the bar 31 therewith into engagement with the contacts 32 and 33, which results in closing the circuit through a source of electrical energy 34. This closed circuit may be traced as follows:—From the contact 33 a conductor 34' leads to a pole 35, of the source of electrical energy, while a conductor 36 leads from the other pole 37 of the source of electrical energy to a green or safe light 38. A conductor 39 is connected with the opposite binding post of the green light 38 and leads to a conductor 40, the said conductor 39 joining the conductor 40 at point 41, from which point 41, the circuit is completed through a conductor 42, contact 32, bar 31, the contact 33 and the conductor 34', which is connected with the pole 35 of the source of electrical energy 34. When the bar 30 is in its normal or full line position in Fig. 4, the circuit is closed through the green or safe light 38, and is also for the time being closed through a motor 43 and normally through an electro-magnet 44, the electrical connections with the motor 43 being as follows:—From a point 45 on the conductor 36, a conductor 46 leads to a binding post 47 mounted on the motor 43, passing thence through the motor and a conductor 48 leading to a contact 49 of a circuit breaker 50. From the contact member 51, of the circuit breaker 50, a conductor 52 leads to a terminal 53 of the electro-magnet 44, from which point the motor circuit is completed through the conductors 40 and 42, the contact 32, bar 31, contact 33 and the conductor 34', to the pole 35 of the source of electrical energy 34. The circuit is completed through the coils of the electro-magnet 44 as follows:—From a point 54 on the conductor 36 a conductor 55 leads to a terminal 56 of the said electromagnet, while from the opposite terminal 53 of the electro-magnet, the circuit is completed through the conductor 40 and conductor 42, which is connected with the conductor 40 at point 41, to the contact 32, the bar 31, the contact 33 and the conductor 34' to the pole 35 of the source of electrical energy 34.

In Fig. 4 of the drawing, we have shown a train 57, conventionally illustrated by means of wheels 58 and an axle 59, whereby the track rail members 16 and 17 are bridged by the said train 57 and the current from the source of electrical energy 20 short circuited and the circuit through the coil of the relay 23 is broken, whereby its core 30 is released and the bar 31 allowed to drop away from the contacts 32 and 33. When the bar 31 is thus disengaged from the contacts 32 and 33, the circuit is broken through the motor 43 and electro-magnet 44 and the safe or green light 38. Since the circuit is broken through

the electro-magnet 44 in the aforesaid manner, an armature bar 60 is released from the influence of the magnet 44 and the semaphore arm 61 allowed to drop to the danger position, by virtue of mechanism hereinafter more fully explained. The movement of the contact bar 31 away from the contacts 32 and 33 results in closing the circuit through the red or danger light 62 in the following manner:—The current from the source of electrical energy 34 passes from the pole 37, through the conductor 36 to a point 63 thereon, from which point a conductor 64 leads to the red lamp 62, from which lamp a conductor 65 leads to a contact 66 from which the circuit is completed through the bar 31, the contact 67, the conductor 68 and the conductor 34' to the opposite pole 35 of the source of electrical energy 34.

We provide certain mechanism for controlling the rise and fall of the semaphore arm to the safe and danger positions, respectively, and we will now proceed to describe this mechanism. A shaft 69 is mounted and connects the opposite sides 70 and 71 of a frame work, designated in its entirety by the reference character 72, and upon this shaft is journaled a grooved pulley 73, in the groove of which one extremity of a flexible device or chain 74 is secured, as shown at 75, while its opposite extremity is connected with a quadrant or sector 76, which latter instrumentality is connected with the semaphore arm 61 on the opposite side of a pivot 77 of said semaphore arm. In view of the foregoing recitation of the elements connecting the pulley 73 with the semaphore arm 61, it will be understood that as the said pulley is turned in the direction of the arrow (see Fig. 4), the semaphore arm will be raised, while, when the resistance to the turning of the said pulley in the opposite direction is relieved the semaphore arm will fall. A large gear 77 is also journaled upon the shaft 69 and is connected with the pulley 73, to turn in unison with the latter. The pulley 73 and the relatively large gear 77 are each mounted upon the same hub 78 and must therefore necessarily turn together. The relatively large gear 77 meshes with a relatively small gear or pinion 79, which is threaded upon a sleeve 80 as shown at 81. This sleeve 80 is supported and journaled upon a shaft 82, which latter is journaled in the opposite side members 70 and 71 of the frame work 72, the said shaft 82 being co-actually journaled with the sleeve 80. Connected with the sleeve 80 is a spider 83 upon the arms of which are journaled planetary gears 84, by means of journal pins 85 which pass through the planetary gears 84 and the extremities of the arm of the spider 83. Surrounding these planetary gears 84, is an internal gear 86, supported by means of a spider 87, which is journaled upon the shaft 130

82. The said internal gear 86, being secured to the arms of the spider by means of set screws or bolts 88.

Meshing with the planetary gears 84, is a gear wheel 89, the said gear wheel 89 being keyed or made fast upon the shaft 82 to turn with the latter. Also mounted upon the shaft 82 and made fast therewith is a worm wheel 90, which meshes with a worm 91 formed upon a motor shaft 92 of the motor 43. Assuming that the motor 43 is turning in the direction of the arrow, (see Fig. 4), the worm 91, causes the worm wheel 90 to revolve, in the direction of the arrow, the worm in turn causing the shaft 82 to revolve in the same direction. Now since the planetary gears 84 are interposed between the internal gear wheel 86 and the gear 89 and the teeth of the planetary gears 84 mesh with the teeth of the aforesaid two gears, the planetary gears 84 will be caused to travel around and upon the periphery of the gear 89 and carry the sleeve therewith, while the internal gear 86 will remain stationary by virtue of mechanism hereinafter more fully explained. The sleeve 80 revolves the pinion 79 which meshes with the relatively large gear 77, to cause the latter to turn in the direction of the arrow (see Fig. 6). And since the pulley 73 is connected to turn in unison with the gear 77, the said pulley will also revolve in the same direction, whereby the chain 74 will be wound around the pulley and will act upon the semaphore arm 61 to raise the latter to the upright or the position to indicate safety.

When the semaphore arm occupies the raised or safety position, the circuit is closed through the coils of the electro-magnet 44, but the circuit is broken through the motor 43 as soon as the semaphore arm reaches the raised position by virtue of mechanism which will be hereinafter more fully explained.

Attention is here called to the fact that during the upward movement of the semaphore arm the circuit is closed through both the motor 43 and the electro-magnet 44, whereby the armature 60 of the magnet 44 is drawn into contact with the said electro-magnet. This armature 60 is pivotally mounted to the frame work as shown at 93 and to its opposite extremity is pivotally connected a rod 94 as shown at 95. To the opposite extremity of this rod 94, we pivotally connect toggle arms 96 and 97 as shown at 98. The upper extremity of the toggle arm 96 is pivotally mounted or connected with the frame work as shown at 99, the said arm having an extension 100, beyond the pivot 99, adapted to be engaged by the lug 101 of an arm 102, one extremity of which is also pivoted at 99, while its opposite extremity is pivotally connected with a collar 103, of a governor 104. The toggle arm 97

is pivotally connected as shown at 105 to one extremity of a band brake 106. This band brake surrounds the internal gear 86 and fits into a groove 107 with which the outer periphery of the internal gear 86 is provided. The opposite extremity of this band brake 106, is pivotally connected with one extremity of a rod 108 as shown at 109, the opposite extremity of the said rod 108 being pivotally connected to the bottom or base of the frame work 72 as shown at 110. Therefore, by virtue of the instrumentalities above recited, the toggle arms 96 and 97 act upon the band brake 106, through the instrumentality of the armature 60 and rod 94, to prevent turning of the internal gear during the upward movement of the semaphore arm.

As heretofore explained, when the semaphore arm is caused to move upwardly, the gear wheel 77 turns in the direction of the arrow (see Fig. 6). Now as soon as the gear wheel 77 has turned far enough to cause the pulley 73 to raise the semaphore arm to the safety position, a projection 111 with which the said gear wheel 77 is provided, comes into contact with the contact 51 of the circuit breaker 50 and acts upon the said contact 51 to separate the same from the opposing contact 49, of the said circuit breaker 50, whereby the circuit is broken through the motor 43, since these two contacts 49 and 50 serve to complete the motor circuit, and of course, when they are separated from each other, the motor circuit will be broken and the movement of the motor stopped. The electro-magnet 44 remains energized while the semaphore arm is in the raised position and consequently, the toggle arms 96 and 97, are being acted upon to tighten the brake band 106 around the internal gear 86 for preventing movement of the latter, and thus, since the internal gear 86 is prevented from turning the semaphore arm, is held or supported in the raised or safety position against the influence of gravity. In other words, in order to allow the semaphore to drop to a danger position, it is necessary to permit the internal gear 86, to revolve and in order to permit the said internal gear to revolve it is necessary to break the circuit through the electro-magnet 44, whereby the brake band 106 will be released from frictional engagement with the said gear 86.

The operation of the mechanism to display the danger signals, when the circuit is broken through the electro-magnet 44, will now be explained. Assuming that the train 57 is in the block 14 and is traveling in the direction of the arrow (see Fig. 4), the current from the source of electrical energy 20 will be short circuited through the train 57 and the relay 23 deenergized, whereby the core 30 will be released and the contact bar 31 allowed to fall into engagement with the contacts 66 and 67, thus breaking the cir-

cuit through the green or safe light 38 and through the electro-magnet 44 and closing the circuit through the red or danger light 62, the latter condition being effected in the following manner:—The current from the source of electrical energy 34, may be said to pass through the conductor 36 to a point 63, thence through a conductor 64, to the red or danger lamp 62 from whence it passes through conductor 65, contact 66, contact bar 31, contact 67, conductor 68 and conductor 34', to the opposite pole 35 of the source of electrical energy 34. The breaking of the circuit through the electro-magnet 44 results in releasing the armature 60, whereby the brake band 106 acts upon toggle arms 96 and 97 under the influence of its tension to cause the said toggle arms to act upon the rod 94 to cause the latter to move the armature 60 away from the magnet, thus releasing the brake band 106 from frictional engagement with the internal gear wheel 86. Since the frictional engagement of this brake band 106 with the internal gear 86, has been released the said internal gear will be permitted to revolve and will be caused to revolve under the influence of the weight of the semaphore arm 61, by virtue of mechanism which will now be explained. The downward movement of the semaphore arm 61 causes the pulley 73 to turn in the direction opposite to the direction indicated by the arrow in Fig. 4, whereby the chain 74 is unwound from the said pulley 73. The turning of the pulley 73 resulting from the downward movement of the semaphore arm 61 by virtue of the chain connection 74, the relatively large gear 77, will also be caused to revolve in the same direction as that of the pulley 73 or in other words, in the direction opposite to the direction indicated by the arrow in Fig. 4. This movement or revolving of the relatively large gear 77 acts upon the pinion 79, which as heretofore explained, is made fast to the sleeve 80, whereby the said sleeve 80 is caused to revolve upon the shaft 82, which in turn carries the planetary gears 84 therewith, the said planetary gears in turn acting upon the internal gear 86 to cause the latter to revolve. However, since the gear 89 is keyed or made fast upon the shaft 82 and since the shaft 82 is locked against movement, in the manner which will later be described, the planetary gears will be caused to travel around and upon the periphery of the said gear 89. One side of the internal gear 86 is provided with a beveled gear 113, which meshes with a pinion 114, mounted upon the lower extremity of a governor shaft 115. Now therefore, when the gear 86 is revolving in the manner above explained, it will impart movement to the governor shaft 115 through the medium of its pinion 114. This movement, imparted to the governor shaft 115,

will act to prevent the rapid downward movement or sudden drop of the semaphore arm 61 and thus prevent injury to the mechanism resulting from the concussion or jar of the sudden drop of the semaphore arm 61.

The manner of controlling the drop or downward movement of the semaphore arm 61 will now be explained. As the governor shaft 115 revolves the balls 116, of the governor 104, will move outwardly and as a result will move the collar 103 upwardly on the shaft 115. This upward movement of the collar 103 will result in bringing the lug 101 of the arm 102 into contact with the extension 100 to the toggle arm 96 whereby the toggle arm 96 will be caused to turn upon its pivot 99 and straighten out or bring the two toggle arms 96 and 97 toward their alined position resulting in tightening the brake band 106 around the internal gear 86 which prevents or retards the said gear from revolving at too great a rate of speed. The said internal gear 86 acting through its connection with the semaphore arm 61 in the manner heretofore explained to slacken or lessen the speed of the downward movement of the semaphore arm 61.

Attention is here called to the fact that the rod 94 and the rod 108 are respectively provided with turn buckles 117 and 118, intermediate their extremities for adjusting the length of the aforesaid rods.

Attention is here called to the fact that the worm 91 will lock the worm wheel 90 against movement during the downward movement of the semaphore arm and since the worm wheel 90 is made fast to the shaft 82 and the gear 89 is also made fast to this shaft. Both the shaft 82 and the gear 89 will also be locked against movement and as a result the planetary gear 84 must travel around and upon the periphery of the gear 89 without acting to turn the latter.

Attention is here called to the fact that in our improved mechanism the safe and danger lights are not in any way controlled by the movement of the semaphore arm 61, but are displayed and extinguished independently of the arm and the mechanism for operating and controlling the said arm. In view of this fact, if the semaphore arm or the mechanism, for operating the same, should in any way, become out of order, the said arm would not perform its function, the safe and danger lights would continue to be controlled and perform their functions as though the semaphore arm and its operating mechanism were properly performing their functions.

Attention is further called to the fact that the semaphore arm 61 is counter-balanced and to accomplish this purpose the said arm is provided with a counter-balancing weight 119, which accomplishes the double purpose of acting to move the said arm downwardly

and to serve as a shade or device for concealing from view, the green or safe light 38, when the semaphore arm occupies the danger position. Thus if the green light 5 should, for any reason, fail to be extinguished when the semaphore arm drops to the danger position the same would be concealed from view by the weight or shade 119. While we have described and illustrated 10 herein a specific form of our invention, it is understood that we are not limited thereto and that the same may be modified and varied without departing from the spirit of our invention as determined by the domain 15 of the appended claims.

Having thus described our invention what we claim is:

1. The combination with a semaphore arm, of mechanism for controlling said 20 semaphore arm consisting of a motor, a gear connected in operative relation with the said motor but incapable of transmitting motion thereto, a revolvably mounted shaft to which the said gear is made fast, an internal gear 25 wheel journaled upon the said shaft, a sleeve also journaled upon the said shaft, planetary gears connected with the said sleeve and adapted to mesh with the teeth of the internal gear wheel, another gear made fast 30 to the shaft and also meshing with the said planetary gears, a pinion mounted upon the said sleeve and connected in operative relation with the semaphore arm, a brake band applied to the aforesaid internal gear, elec- 35 tronagnetic means connected in operative relation with the said brake band for preventing movement of the internal gear wheel when the said electro-magnetic means is energized and for releasing the said brake band 40 from frictional engagement with the said internal gear wheel when the said electro- magnetic means is deenergized, whereby the semaphore arm is allowed to drop to the danger position, and means connected in op- 45 erative relation with the aforesaid internal gear wheel and adapted to act upon the brake band for controlling the downward movement of the semaphore arm, substan- tially as described. 50
2. In railway signaling apparatus, the combination with a signal, of mechanism for controlling said signal, comprising a motor and brake, and means controlled by said motor and brake in operative relation with 55 the signal to move the latter to the safety position, said means being also controlled by the brake for retarding the movement of the signal to the danger position, electro- magnetic means which when energized ap- 60 plies said brake for supporting the signal in the safety position and which when de- energized allows the signal to move to the danger position, a governor connected in operative relation with the signal and adapt- ed to be actuated by movement of the signal 65
3. In railway signaling mechanism the combination of a signal means for actuating the signal to cause it to assume the safe position, comprising a motor, a shaft connected to be revolved by the said motor but incapable of transmitting motion thereto, a member journaled upon the said shaft, planetary gears carried by the said member, a gear made fast to the shaft and an internal gear wheel journaled upon the shaft, the planetary gears being interposed between the said gear which is made fast to the shaft and the internal gear wheel, an operative connection between the member journaled upon the said shaft and the signal whereby when the shaft 70 is revolved the gear, made fast to the said shaft, is actuated to cause the planetary gear to travel around its orbit when the internal gear wheel is held against movement, and operate the connection between the said member and the signal to move the latter to the safety position, a brake applied to the internal gear wheel, and electromagnetic means which when energized applies the said brake to prevent movement of the said internal gear wheel for maintaining the signal in the safety position. The said electromagnetic means releasing the brake when deenergized to permit the signal to move to the danger position, and a connection be- 75
4. In signal mechanism, the combination with a signal, of mechanism for controlling said signal, comprising a motor and brake, and means controlled by said motor and brake in operative relation with said signal, and adapted to move the latter to the safety position, said means being also controlled by the brake for retarding the movement of the signal to the danger position, a governor 80 connected in operative relation with said signal and adapted to be actuated by the movement of said signal to the danger position, and a toggle connection between the brake and the governor adapted to be acted upon by the governor to apply the brake for retarding the rapid movement of the signal to the danger position. 85
5. In signal mechanism, the combination with a signal, of mechanism for controlling the said signal, comprising a motor and brake, and means controlled by said motor and brake and in operative relation with the said signal to move the latter to the safety position, said means being also controlled by the brake for retarding the move- 90

ment of the signal to the danger position, an electro-magnet, a connection between the said electro-magnet and the brake for applying the brake when the electro-magnet 5 is energized and for releasing the said brake when the electro-magnet is de-energized, a governor connected to be operated by the movement of the signal to the danger position, and a connection between 10 the brake and the governor adapted to be acted upon by the governor to apply the brake independently of the electro-magnet for retarding the movement of the signal to the danger position.

15 6. In signal mechanism, the combination of a semaphore arm, a motor, a connection between the motor and the semaphore arm, comprising a shaft adapted to be revolved by said motor but incapable of transmitting motion thereto, a member journaled on said shaft, planetary gears carried by said member, a gear wheel made fast to the said shaft and an internal gear wheel journaled on said shaft, the planetary gears being interposed between the said gear wheels, an operative connection between the said member journaled upon the said shaft and the semaphore arm, a brake applied to the said internal gear wheel, means for setting the brake 20 to prevent movement of the said internal gear wheel for holding the semaphore arm in the safe position and for releasing the said brake to permit the said internal gear wheel to revolve for allowing the semaphore 25 arm to move to the danger position, a governor operated by the said internal gear wheel, and a connection between the said governor and the said brake, said connection being adapted to be acted upon by the governor to set the said brake for retarding the movement of the semaphore arm to the danger position, substantially as described.

40 7. In signal mechanism, the combination of a semaphore arm, means for actuating the semaphore arm to cause it to assume the safe position, comprising a motor, a shaft adapted to be revolved by said motor but incapable of transmitting motion thereto, a member journaled on said shaft, a planetary gear journaled on said member, a gear wheel made fast to the shaft, an internal gear wheel journaled on said shaft and surrounding the gear wheel made fast to said shaft, the planetary gear being interposed between 45 the said gear wheel which is made fast to the said shaft and the internal gear wheel which is journaled on said shaft and occupying a plane corresponding with the plane 50 of the gear wheel made fast to said shaft and the internal gear wheel, an operative connection between the member journaled on the said shaft and the semaphore arm, whereby when the said shaft is revolved the gear wheel made fast to the said shaft causes 55 the planetary gear to travel around its orbit 60 65

and operate the connection between the said member journaled upon said shaft and the semaphore arm to move the latter to the safety position when the internal wheel gear is stationary, means for preventing movement of the internal gear wheel to enable it to coöperate with the other gears to cause the semaphore arm to move to and be maintained in the safety position, means for releasing the internal gear wheel to permit the semaphore arm to move to the danger position, the said internal gear wheel having a bevel gear on one side thereof, a governor, a pinion meshing with said bevel gear, a connection between said pinion and said governor, and connections between the governor and the means to prevent movement of the internal gear wheel, whereby the downward movement of said semaphore arm is controlled, substantially as described. 85

8. In signal mechanism, the combination of a semaphore arm, of means for actuating said semaphore arm to cause it to assume the safe position, comprising a motor, a shaft connected to be revolved by said motor but incapable of transmitting motion thereto, a member journaled on said shaft, a planetary gear carried by said member, an element made fast to said shaft and an element journaled on said shaft and encircling the element made fast to said shaft, the planetary gear being interposed between said elements and engaging both of the latter, an operative connection between the member journaled upon said shaft and the semaphore arm, whereby when the shaft is revolved the element made fast to the said shaft is actuated to cause the planetary gear to travel around its orbit and operate the connection between the said member and the semaphore arm to cause the latter to move to the safe position when the element journaled on the shaft is held in fixed position, means for preventing revolving of the element journaled on said shaft to enable it to coöperate with the planetary gear and the other element to cause the semaphore arm to move to and be maintained in the safe position, means for releasing the said element journaled on said shaft to permit the semaphore arm to move to the danger position, a governor connected in operative relation with said element journaled on said shaft, and connections between the said governor and the said preventing means, said governor being actuated by the said element journaled on said shaft for controlling the downward movement of the semaphore arm. 100 105 110 115 120

9. In signal mechanism, the combination with a signal, of means for actuating said signal, comprising a motor, a shaft operable by said motor but incapable of transmitting motion thereto, a member journaled on said shaft, a planetary gear carried by said member, a gear element made fast to said shaft 125 130

and a gear element journaled on said shaft and encircling the gear element made fast to said shaft, the planetary gear being interposed between the said gear elements and meshing with both of the latter, a gearing connection between the member journaled upon said shaft and the signal, a brake for holding the gear element journaled upon the said shaft against revolving, whereby when 10 the said shaft is revolved the gear element made fast to the shaft is actuated to cause the planetary gear to travel around its orbit and operate the said member journaled upon the said shaft which in turn operates the 15 gearing connection between said member and the signal to cause the latter to assume and maintain the safe position when the gear element journaled on said shaft is stationary, means for releasing the said brake, whereby 20 the signal is allowed to assume the danger position, a governor connected to be operated by the gear element journaled on said shaft, a connection between said governor and said brake, said connection adapted to 25 be acted upon by said governor to apply the brake for controlling the movement of the signal to the danger position.

10. The combination with a signal, of mechanism for controlling said signal, consisting of a motor connected in operative relation with said signal and adapted to move the latter to the safety position, said connection comprising a shaft said shaft being incapable of transmitting motion to said motor, an internal gear wheel journaled upon said shaft, a sleeve also journaled upon said shaft, another gear wheel made fast to the said shaft and surrounded by the said internal gear 35 wheel, planetary gears connected with the sleeve and interposed between the internal gear wheel and the gear wheel made fast to the shaft, means for holding the internal gear wheel against movement, whereby when the said shaft is revolved the gear wheel made fast to the said shaft is actuated to cause the planetary gears to travel around their orbit and operate the said sleeve, a gearing connection between the said sleeve 40 and signal, whereby the operation of the said sleeve in turn operates said gearing connection to cause the signal to assume and maintain the safety position when the said internal gear wheel is stationary, means for releasing the internal gear wheel to permit the latter to turn, a bevel gear mounted upon one side of said internal gear wheel, a pinion meshing with said bevel gear, a governor, said pinion being connected in 45 operative relation with said governor, whereby when said internal gear revolves, the governor is actuated to control the movement of the signal to the danger position.

11. In signal mechanism, the combination of a semaphore arm, means for actuating the 50 semaphore arm to cause it to assume the safe position, comprising a motor, a shaft adapted to be revolved by said motor said shaft being incapable of transmitting motion to said motor, a member journaled on said shaft, a planetary gear carried by said member, a gear wheel made fast to the said shaft, a second gear wheel journaled on the said shaft and surrounding the gear wheel made fast to said shaft, the planetary gear 55 being interposed between the said gear wheels, an operative connection between the said member journaled on the said shaft and the semaphore arm, whereby when the said shaft is revolved the gear wheel made fast to the said shaft causes the planetary gear to travel around its orbit and operate the connection between the said member and the semaphore arm to move the latter to the safety position when the gear wheel journaled on said shaft is stationary, means for preventing movement of the second gear wheel to enable it to coöperate with the other gears to cause the semaphore arm to move to and be maintained in the safe position, 60 means for releasing the said gear wheel to permit the semaphore arm to move to the danger position, the second gear wheel having gear teeth on one side thereof, a governor, and a pinion connected in operative 65 relation with said governor and meshing with the gear teeth on the side of the second gear wheel, whereby the revolving of the second gear wheel actuates the said governor for controlling the movement of the semaphore arm to the danger position.

12. In signal mechanism, the combination with a semaphone arm, of means for actuating said semaphone arm to cause it to assume the safe position, comprising a motor, a shaft connected to be revolved by said motor said shaft being incapable of transmitting motion to said motor, a member journaled on said shaft, a planetary gear carried by said member, an element made fast to said shaft and an element journaled on said shaft and surrounding the element made fast to said shaft, the planetary gear being interposed between said elements and engaging both of the latter, an operative connection between said member journaled on said shaft and the semaphone arm, whereby when the said shaft is revolved the element made fast to the said shaft is actuated to cause the planetary gear to travel around its orbit and actuate the said member journaled on said shaft, which in turn operates the connection between the said member and the semaphone arm to cause the latter to assume the safe position when the said element journaled on said shaft is stationary, means for preventing movement of the element journaled on the said shaft to enable it to coöperate with the other elements to cause the semaphone arm to move to and 70

be maintained in the safe position, means for releasing said element journaled on the shaft to permit the semaphore arm to move to the danger position, a governor, and a gearing connection between said governor and said element journaled on said shaft, whereby the governor is actuated through the medium of said element journaled on said shaft for controlling the movement of the semaphore arm to the danger position.

10 13. Signal mechanism, comprising a movable signal member, a shaft, means for revolving said shaft in one direction, said shaft being incapable of being revolved in the opposite direction, a member journaled on said shaft, a planetary gear carried by said member, a gear element made fast to said shaft and a gear element journaled on said shaft and surrounding the gear element made fast to said shaft, the planetary gear being interposed between said gear elements and meshing with both of the latter, an operative connection between said member journaled on said shaft and the movable signal member, whereby when the said shaft is revolved the gear element made fast to said shaft is actuated to cause the planetary gear to travel around its orbit and actuate the said member journaled on said shaft, which in turn operates the connection between the said member and the movable signal member to cause the latter to assume the safety position when the said element journaled on said shaft is stationary, means for holding the gear element journaled on said shaft against revolving to enable it to coöperate with the other gears to cause the semaphore arm to move to and be held in the safety position, means for releasing said gear element journaled on said shaft to permit said gear element to revolve, whereby the movable signal member is allowed to move to the danger position, a governor, a gearing connection between said governor and said gear element journaled on said shaft, whereby when said gear element journaled on said shaft revolves the governor is actuated, and a connection between said governor and said means for holding the gear element journaled on said shaft against revolving, substantially as described.

14. In signal mechanism, the combination of a movable signal member, of mechanism for controlling said movable signal member, comprising a shaft adapted to be revolved in one direction, means holding said shaft from revolving in the opposite direction, a gear wheel journaled upon said shaft, a member also journaled upon said shaft, another gear wheel made fast to said shaft and surrounded by the said gear wheel journaled upon said shaft, a planetary gear journaled upon the said member, which is journaled upon the said shaft, said planetary gear being interposed between the gear wheel jour-

naled upon the said shaft and the gear wheel made fast to the said shaft, means for holding the gear wheel journaled upon said shaft against revolving, whereby when the said shaft is revolved the gear wheel made fast to the said shaft is actuated to cause the planetary gear to travel around its orbit and operate the said member journaled upon said shaft, a gearing connection between the said member journaled upon the said shaft and the movable signal member, whereby the operation of said member journaled upon said shaft in turn operates said gearing connection to cause the movable signal member to assume the safety position, means for releasing the gear wheel journaled upon said shaft to permit the latter to revolve, whereby the movable signal member is allowed to assume the danger position, the gear wheel journaled upon said shaft being provided with gear teeth on one side thereof, a governor, a pinion meshing with said gear teeth on the side of the said gear wheel journaled upon said shaft, a connection between said pinion and the governor, whereby when said gear wheel journaled upon said shaft revolves, the governor is actuated, and a connection between said governor and said means for holding the gear wheel journaled upon said shaft against revolving, whereby the governor operates to apply said means for controlling the movement of the signal member to the danger position, substantially as described.

15. In signal mechanism, the combination with a signal, of means for actuating said signal, comprising a motor, a shaft operable by said motor, a member journaled on said shaft, a planetary gear carried by said member, a gear element made fast to said shaft and a gear element journaled on said shaft and encircling the gear element made fast to said shaft, the planetary gear being interposed between the said gear elements and meshing with both of the latter, a connection between the said member journaled upon said shaft and the signal, a brake for holding the gear element journaled upon the said shaft against revolving, whereby when the said gear element journaled upon the said shaft is held against revolving, and the said shaft is revolved, the gear element made fast to the said shaft is actuated to cause the planetary gear to travel around its orbit and operate the said member journaled upon the said shaft which in turn operates the connection between said member and the signal to cause the latter to assume the safe position, the motor driven shaft being incapable of driving the motor, whereby the said signal is maintained in the safe position when the said gear element journaled upon the said shaft is held against revolving, means for releasing the said brake, whereby the signal is allowed to assume the danger position, 130

and a governor connected to be operated by the said gear element journaled upon said shaft for controlling the movement of the signal to the danger position.

- 5 16. The combination with a signal, of mechanism for controlling said signal, comprising a motor, a shaft operable by said motor but incapable of transmitting motion to the latter, a member journaled on said shaft, 10 a planetary gear carried by said member, a gear wheel made fast to the said shaft and an internal gear wheel journaled on said shaft, the planetary gear being interposed between said gear wheels and meshing with 15 both of the latter, a connection between said member journaled on said shaft and the signal, means for holding the said internal gear wheel against revolving, whereby when said internal gear wheel is held against revolving, 20 and the said shaft is revolved, the said gear wheel made fast to the said shaft is actuated to cause the planetary gear to travel around its orbit and operate the said member journaled on said shaft which in turn operates

the connection between said member and the signal to cause the latter to assume the safe position, the said signal being maintained in the safe position while the said internal gear wheel is held against revolving, means for releasing the said internal gear wheel to permit the latter to revolve, whereby the signal is allowed to assume the danger position, the said internal gear wheel having also external gear teeth, a governor, and a pinion connected in operative relation with said governor and meshing with the external gear teeth of said internal gear wheel, whereby the revolving of said internal gear wheel actuates the said governor for controlling the movement of the signal to the danger position. 40

In testimony whereof we affix our signatures in the presence of two witnesses.
